UNITED STATES PATENT OFFICE.

JAMES S. STANLEY, OF INDIANAPOLIS, INDIANA.

BRUSH.

1,322,641.

Specification of Letters Patent. Patented Nov. 25, 1919.

Application filed February 11, 1919. Serial No. 276,358.

To all whom it may concern:

Be it known that I, JAMES S. STANLEY, a citizen of the United States, residing at Indianapolis, in the county of Marion and 5 State of Indiana, have invented certain new and useful Improvements in Brushes; and I do hereby declare the following to be a full, clear, and exact description of the invention, such as will enable others skilled 10 in the art to which it appertains to make and use the same.

This invention relates to brushes, and more particularly to a brush adapted to be used for shaving and similar purposes.

15 One of the main objects of the invention is to provide a brush of the character stated in which the bristles of the brush head may have their effective lengths readily shortened so as to produce, in effect, a comparatively 20 stiff brush for working the lather into the shaver's beard by massaging so as to insure softening of the hairs of the beard preparatory to shaving.

A further object is to provide simple and 25 efficient means for holding the bristles of the brush head in the manner stated, this means being positively secured in operative position so as to effectually eliminate accidental displacement thereof.

30 Further objects will appear from the detailed description.

In the drawings:

Figure 1 is a sectional view through a 35 shaving brush constructed in accordance with my invention, the collar for holding the bristles being shown in retracted or inoperative position.

Fig. 2 is a similar view with the collar extended.

40 The brush designated generally by A may be of any suitable or standard construction, but preferably includes a substantially cylindrical body 1 in one end of which is secured a handle 2, the brush head 3 being secured 45 in the other end of the body. Body 1 is provided, adjacent its inner end, with an outer annular threaded shoulder 4 and, adjacent its outer end, with a similar shoulder 5. The shoulders 4 and 5 are adapted to 50 be engaged by a similarly threaded inner annular shoulder 6 provided at the inner end of a relatively broad collar 7 the interior diameter of which corresponds to the exterior diameter of the shoulders 4 and 5, this 55 collar normally fitting snugly about body 1

and being of slightly greater length than the body. When the collar 7 is in its normal or inner position, the inner end of this collar fits snugly against the relatively broad annular shoulder 2^a provided at the inner 60 end of handle 2, the exterior of the collar being substantially flush with the outer edge of the shoulders so as to form a continuation thereof thus presenting a neat appearance and closely resembling a shaving brush of 65 ordinary construction.

In using the brush, a lather is worked up in the well known manner with the sleeve 7 in its inner position, as in Fig. 1, thus permitting ready flexing or bending of the 70 bristles of head 3. After the lather has been worked up, collar 7 is unthreaded from shoulder 4 and is moved into its outer position, being secured upon shoulder 5. In this position, the outer end of the collar engages snugly about the bristles of the brush head 3 so as to tightly confine the same thus producing, in effect, a relatively short and comparatively stiff head which may be readily utilized for massaging and working the 80 lather into the beard so as to effectually soften the hairs thereof. As will be noted more clearly from Fig. 2, the outer end of collar 7 is beveled inwardly, as at 7^a, thus causing a slight spreading of the outer end 85 portion of the brush head so as to provide a rounded formation which is well adapted for working the lather into the beard, this rounding of the head also permitting slight giving or flexing of the bristles, such as is 90 desirable when using the brush in the manner stated. As will be noted, the screw threaded shoulders 4 and 5 of body 1, cooperate with shoulder 6 of sleeve 7 to positively secure this sleeve in adjustment upon 95 the body so as to effectually eliminate all possibility of accidental displacement of the sleeve when the brush is in use. Also, when it is desired to remove the sleeve or collar 7 for cleaning or repairing the brush, this may be readily accomplished by threading shoulder 6 off of shoulder 5, after which the collar may be slid over the brush head, this collar or sleeve being readily replaced when desired by reversing this operation.

100 As will be readily appreciated, it may be desirable in practice to resort to slight changes in details of construction and arrangement of parts of the device, and I intend to include all such variations, as fall 110

within the scope of the appended claims, in this application in which a preferred form only of my invention is disclosed.

What I claim is:

- 5 1. The combination with a brush including a body and a head carried thereby, said body being exteriorly threaded adjacent each end only, of a collar slidable longitudinally of the body and provided adjacent its inner end with interior threads adapted to engage the threads of said body for securing the collar in adjustment thereon, said collar being adapted when in extended position to fit snugly about the head of the brush adjacent the outer end thereof for confining the bristles of the brush head.
- 10 2. The combination with a brush including a body, a brush head secured in one end thereof, and a handle secured in the other end of the body and provided adjacent its inner end with an outer annular shoulder

extending beyond the inner end of said handle, said body being exteriorly threaded adjacent each end only; of a collar fitting about said body and slidable longitudinally 25 thereof, said collar being interiorly threaded at its inner end for engagement with the threads of the body for positively securing the collar in adjustment thereon, the shoulder of the handle positively limiting inward 30 movement of the collar, the collar being adapted when in extended position to engage snugly about the brush head adjacent the outer end thereof for confining the bristles 35 of said head.

In testimony whereof I affix my signature in presence of two witnesses.

JAMES S. STANLEY.

Witnesses:

HENRY BRANDT,
L. G. LAWRENCE.
